UNITED STATES PATENT OFFICE.

JOHN G. HAMMOND, OF CHICAGO, ILLINOIS, ASSIGNOR TO THOS. CUSACK CO., A CORPORATION OF NEW JERSEY.

DESIGN FOR A SIGN.

45,714.

Specification for Design.

Patented May 5, 1914.

Application filed March 4, 1914. Serial No. 822,510. Term of patent 3½ years.

To all whom it may concern:

Be it known that I, JOHN G. HAMMOND, a citizen of the United States, and a resident of the city of Chicago, county of Cook, and State of Illinois, have invented a new, original, and ornamental Design for Signs, of which the following is a specification, reference being had to the accompanying drawing, forming part thereof.

In the drawing: Figure 1 represents a

view in perspective of my novel sign design. Fig. 2 is a view in end elevation thereof.

I claim:—

The ornamental design for a sign, as shown.

JOHN G. HAMMOND.
